ABSTRACT OF THE DISCLOSURE

Chlorinated or brominated alkenes containing 2-4 carbon atoms stabilized with trimethyl orthoformate and a compound selected from the group consisting of C₁-C₄ alkanols, C₁-C₄ alkyl cyanides, 1,4-dioxane, trioxane and C₁-C₄ nitroalkanes.

This invention relates to the stabilization of halogenated saturated aliphatic hydrocarbons.

It is well known that saturated aliphatic hydrocarbons containing halogenated groups, such as chlorine, are unstable when contacted with metal such as aluminum or its alloys, magnesium and its alloys, amongst others. The instability results in decomposition of the halogenated hydrocarbon with the concurrent formation of halogenated hydrides and discoloration of the halogenated hydrocarbon. This introduces serious disadvantages in the use of such halogenated hydrocarbons in such applications as degreasing solvents and/or cleaning solvents for metallic parts or elements.

It is an object of this invention to overcome the above mentioned deficiencies while achieving effective stabilization of the halogenated aliphatic hydrocarbons and thereby enabling use thereof in degreasing and/or cleaning of metal parts, plastics, textiles and other materials, without observing degradation of the solvent or degradation or discoloration of the materials treated.

In accordance with the practice of this invention, the desired stabilization of the halogenated aliphatic hydrocarbons is achieved by the combination with the halogenated hydrocarbon to include one or more ortho-esters having the formula

in which R is a group selected from the group consisting of hydrogen or an alkyl group containing 1 to 3 carbon atoms and R₁, R₂ and R₃ are groups selected from the group consisting of an alkyl group containing 1 to 3 carbon atoms such as methyl, ethyl and propyl groups with or without substituent groups thereon. These R, R₁, R₂ and R₃ groups may be the same or they may differ one from another in the compound. By way of example, the following ortho-ester compounds are suitable for the stabilization of halogenated aliphatic hydrocarbons in accordance with the practice of this invention, namely: triethylorthoformate, trimethylorthoacetate, ethyldimethylorthoacetate and preferably trimethylorthoformate.

In order to achieve the desired stabilization, the ortho-ester is incorporated in the halogenated hydrocarbon in an amount within the range of 0.001 to 15% by weight and preferably 1 to 5% by weight based upon the halogenated hydrocarbon.

Other organic compounds can advantageously be employed in synergistic combination with the ortho-esters in the stabilization of the halogenated hydrocarbons in accordance with a further feature of this invention. The stabilization effect of the ortho-esters and the stabilization of the halogenated hydrocarbons by means of the combination of stabilizers of this invention has been found to be particularly advantageous by reason of the fact that the stabilizing action of the combination is markedly greater than the stabilization action of any of the constituents taken alone in a concentration equivalent to that used in the stabilizing combination. The described synergistic combination is achieved by the combination of the ortho-ester with 0.001 to 3% by weight and preferably 0.1 to 1% by weight of one or more of the compounds containing at least one of the following functions, groups or radicals, namely: aliphatic C₁-C₄ alcohols, aliphatic C₁-C₄ thiols, aliphatic C₁-C₆ esters, aliphatic C₁-C₄ nitriles such as C₁-C₄ alkyl cyanides, aliphatic or cyclic ether-oxides such as C₃-C₆ epoxides, aliphatic C₃-C₈ ketones, C₃-C₁₀ aliphatic or cyclic acetals, C₂-C₆ aliphatic organic acid, aliphatic C₂-C₁₀ imino-ether and ketimines, C₁-C₄ nitroalkyls, oxygenated heterocycles such as pyrane, nitrogenous heterocycles such as pyrrolic, pyrrolinic; aliphatic C₂-C₆ isocyanate, thiocyanate, isothiocyanate; C₅-C₉ alkyl-orthocarbonates and C₃-C₇ alkyl carbonates.

Among the halogen derivatives of saturated aliphatic hydrocarbons which are stabilized by the process of this invention are the following, which are given by way of illustration, but not by way of limitation, namely: dichloroethanes, trichloroethanes, 1,2-dichloropropane, 1,2 and 2,3-dichlorobutanes, tribromoethanes and 1,2-dibromopropane.

The following examples are given to illustrate the different aspects and the advantages of this invention and such examples should be taken by way of illustration but not by way of limitation.

EXAMPLES 1 TO 9

With the intent of showing the stabilizing effect of trimethylorthoformate (TMOF), on the one hand, and of trimethylorthoformate with 1,4-dioxane, nitromethane, trioxane, acetonitrile, tertiobutanol, respectively, on 1,1,1-trichloroethane, the following tests were carried out: the stabilizing agents, in the amounts set forth in the following table, were added to 40 ml. of 1,1,1-trichloroethane and heated to reflux in the presence of an aluminum plate having a thickness of 1 mm., a length of 7.5 mm. and a width of 12 mm. in which the aluminum was of 99.9% purity. The plate is partially immersed in the solvent. The refluxing was continued until the evolution of acid vapors and/or the development of a discoloration in the solvent and the time for the occurrence of one or the other of such events was recorded as representative of the stabilization ability of the stabilizing agent or stabilizing combination.

The following table summarizes the results obtained. By way of comparison and for better illustration of the merits of the invention, the same tests were performed with the same solvent under the same conditions with the following materials substituted for the stabilizing agent, namely: nitromethane, tertiobutanol, 1,4-dioxane, trioxane and acetonitrile. The foregoing compounds correspond to the compounds employed in the combination with trimethylorthoformate in Examples 1 to 9. A reference blank consisting solely of 1,1,1-trichloroethane without stabilizer was also included in the test.

Stabilizer	Content of stabilizer ¹	Grams of stabilizer ²	Time preceding ³
Example:			
1. Trimethylorthoformate (TMOF).		0.5 0 2	30 min. 20 hr. >48 hr.
2. TMOF	50	1.5	>100 hr.
3. Nitromethane	50	2	>100 hr.
4. TMOF	50	1	>100 hr.
5. Acetonitrile	50	1.5	>100 hr.
6. 1,4-dioxane	50	1.5	>100 hr.
7. TMOF	50	1	>100 hr.
8. Acetonitrile	25	1	>100 hr.
9. Tertiobutanol	25	4	100 hr.
10. Trimethylorthoacetate	70	3	>100 hr.
Methanol	20		
Methylformate	10		
Reference blank		0	3 min.
Nitromethane		0.5	28 min.
Tertiobutanol		1	40 hr.
1,4-dioxane		0.5	4 hr.
Acetonitrile		1	48 hr.
Trioxane		0.5	3 hr.
Methylformate		1	20 hr.
Methanol		0.5	38 min.
Do		1	50 hr.
Methylformate		2	15 min.
Methanol methylformate		2	1 hr.
		0.6+0.3	30 hr.
			30 min.
			20 hr.
			30 min.
			5-10 min
			3-3 h. 30

¹ Or of stabilizing composition percent by weight² Or of stabilizing composition per 100 gram 1,1,1-trichloroethane.³ The appearance of acid vapors or of a discoloration.

EXAMPLES 10 AND 11

Stabilization tests of 1,1-dichloroethane according to Examples 1 to 9 have been carried out and the obtained results have been indicated in the following table:

Stabilizer	Grams of stabilizer ¹	Time preceding ²
Example:		
10. Trimethylorthoformate	0.5	40 hr.
11. Trimethylorthoacetate	2	60 hr.
Reference blank	0	10 min.

¹ Per 100 grams 1,1-dichloroethane.² The appearance of acid vapors or of a discoloration.

It will be apparent from the results tabulated in the foregoing tables that the stabilization effect of the compound at 2 grams per 100 grams of solvent is almost twice as great as the compounds used as additives and tested alone and it will be apparent that the combination of stabilizers, representing the preferred practice of this invention, gives a stabilizing effect at 1.5 grams and 2 grams per 100 grams of solvent which is much greater than the stabilizing effect of any of the compounds alone when used in the same concentrations.

It will be apparent from the foregoing that there is provided a new and improved system for the stabilization of halogenated hydrocarbon solvents which is effective at low concentrations to maintain the stability of the hydrocarbon, even in the presence of metals.

It will be understood that changes may be made in the details of the formulations and combinations without departing from the spirit of the invention, especially as defined in the following claims.

We claim:

1. A composition formulated of a chlorinated or brominated alkane containing 2-4 carbon atoms selected

from the group consisting of dichloroethanes, trichloroethanes, 1,2-dichloropropane, 1,2-dichlorobutane, 2,3-dichlorobutane, tribromoethanes, and 1,2-dibromopropane and a stabilizing composition comprising 0.001 to 15% by weight of trimethyl orthoformate and 0.001 to 3% by weight of at least one compound selected from the group consisting of C₁-C₄ alkanols, C₁-C₄ alkyl cyanides, 1,4-dioxane, trioxane, and C₁-C₄ nitro alkanes.

2. A composition formulated of 0.001 to 15% by weight of trimethylorthoformate as claimed in claim 1 and 0.001 to 3% by weight of an alkanol having from 1-4 carbon atoms.

3. A composition formulated of 0.001 to 15% by weight of trimethylorthoformate as claimed in claim 1 and 0.001 to 3% by weight of a C₁ to C₄ alkyl cyanide.

4. A composition formulated of 0.001 to 15% by weight of trimethylorthoformate as claimed in claim 1 and 0.001 to 3% by weight of a compound selected from the group consisting of 1,4-dioxane and trioxane.

5. A composition formulated of 0.001 to 15% by weight of trimethylorthoformate as claimed in claim 1 and 0.001 to 3% by weight of a C₁ to C₄ nitroalkane.
